CANOE PADDLE

Anton G. Borse, 50 Ridgemoor, Willowbrook, Ill.

Filed Aug. 5, 1965, Ser. No. 86,472

Term of patent 14 years

(Cl. D71—1)

FIG.1

FIG.2

6
7
7

FIG.3

FIG.4

FIG.5

FIG.6

FIG.7

FIG. 1 is a perspective view of a canoe paddle embodying the new design;

FIG. 2 is a top plan view of the canoe paddle embodying the new design;

FIG. 3 is a side elevational view of the canoe paddle embodying the new design;

FIG. 4 is an end elevational view of the canoe paddle embodying the new design;

FIG. 5 is another end elevational view of the canoe paddle embodying the new design;

FIG. 6 is a transverse sectional view taken substantially along line 6—6 of FIG. 2; and

FIG. 7 is a transverse sectional view taken substantially along line 7—7 of FIG. 2.

The characteristic feature of my design resides in the shank portion of the handle that extends from the blade

and as best illustrated by the cross-section of FIG. 7, and in the opposed indentations provided in the handle portion remote from the blade and as best shown in FIG. 3.

I claim:

The ornamental design for a canoe paddle, as substantially shown and described.
